UNITED STATES PATENT OFFICE.

HARRY T. HOLLINGSHEAD, OF CHICAGO, ILLINOIS.

DESIGN FOR A RADIATOR CAP.

Application filed September 10, 1925. Serial No. 14,746. Term of patent 7 years.

To all whom it may concern:

Be it known that I, HARRY T. HOLLINGSHEAD, a citizen of the United States, residing at Chicago, in the county of Cook and State of Illinois, have invented a new, original, and ornamental Design for a Radiator Cap, of which the following is a specification, reference being had to the accompanying drawing, forming part thereof.

Figure 1 is a front view of a radiator cap, showing my new design.

Fig. 2 is a plan view thereof.

Fig. 3 is a side view thereof.

I claim:

The ornamental design for a radiator cap, substantially as shown.

HARRY T. HOLLINGSHEAD.
